CLAIM

The ornamental design for a backplate for an HVAC control device, as shown and described.

DESCRIPTION

FIG. 1 is a front view of a backplate for an HVAC control device;

FIG. 2 is a front perspective view of the backplate for an HVAC control device of FIG. 1; and,

FIG. 3 is a rear perspective view of the backplate for an HVAC control device of FIG. 1.

The portions illustrated in broken lines on the figures are for illustrative purposes only and form no part of the claimed design.
